(57) **CLAIM**

The ornamental design for foldable seating cushion, as shown and described.

DESCRIPTION

FIG. 1 is a top view of the foldable seating cushion, showing my new design in unfolded position;

FIG. 2 is a bottom view thereof in unfolded position;

FIG. 3 is a left side view thereof in unfolded position;

FIG. 4 is a right side view thereof in unfolded position;

FIG. 5 is a front view thereof in unfolded position;

FIG. 6 is a back view thereof in unfolded position;

FIG. 7 is an isometric view thereof in unfolded position;

FIG. 8 is an isometric view thereof in semi-folded position; and,

FIG. 9 is an isometric view thereof in folded position.
